UNITED STATES PATENT OFFICE.

EDWARD G. CAUGHEY, OF SEWICKLEY, PENNSYLVANIA, ASSIGNOR OF ONE-HALF TO
EDWARD H. SCHANE, OF YOUNGSTOWN, OHIO.

SHEET-METAL WALL.

1,153,601.

Specification of Letters Patent. Patented Sept. 14, 1915.

Application filed April 8, 1914. Serial No. 830,461.

To all whom it may concern:

Be it known that I, EDWARD G. CAUGHEY, residing at Sewickley, in the county of Allegheny and State of Pennsylvania, a citizen of the United States, have invented or discovered certain new and useful Improvements in Sheet-Metal Walls, of which improvements the following is a specification.

My invention relates to the construction of sheet-metal walls; and, while applicable generally to walls of any size, partitions, and such like structures, finds particular application in the walls of sheet-metal boxes of the sort ordinarily employed in shipment of merchandise.

The object of my improvements is to produce an angular sheet-metal wall (for a box or other use) provided with a reinforcing rib, the entire wall being formed of a single continuous sheet by the rolling of a channel in the sheet of material before the wall is shaped, which reinforcing rib shall extend transversely to the angle and in continuity around the angle in the wall.

The accompanying drawings show the invention applied in the making of a sheet-metal box or packing-case.

Figures 1-8 show the box in preferred form; and Figs. 9-11 show it in alternative. Fig. 1 is a view in perspective of the side-walls of the box, when formed, and before top and bottom are applied; Fig. 2 is a view in plan of the sheet of material of which the side-walls of the box are formed, with the lines of cutting and bending indicated upon it; Fig. 3 is a view on larger scale in section vertically through the box-wall, the plane of section being indicated at III-III, Fig. 1; Figs. 4 and 5 are enlarged views in perspective, and Figs. 6, 7, and 8 are views on substantially the same scale in horizontal section, of a portion of one corner of the finished box-wall, showing alternative manners of arranging and securing the material at the corner. It will be observed that Fig. 8 is a view in section of the structure shown in Fig. 5, the plane of section being indicated in the figure last named by the line VIII-VIII. Fig. 9 is a fragmentary view in perspective of a corner of a box in which the invention is employed in modification; Fig. 10 is a view in section on the plane indicated by the line XV-XV, Fig. 9; and Fig. 11 is a view corresponding to Fig. 2, showing the blank

from which the box of Fig. 9 is to be formed, with the lines of slitting and bending indicated.

All of these figures show inwardly protruding channels, and such is my preferred construction.

I here show and describe the invention applied to the structure of a box; it will be understood from what has been said that the invention is applicable not to boxes merely, nor to receptacles merely, but to walls generally, and my claims are not limited in this respect to the particular application chosen for illustration.

Referring first to Fig. 2, in it is shown in plan the sheet of metal to be shaped to form the box-wall (Fig. 1). It is shaped with longitudinal channels, extending preferably from end to end of the sheet, formed preferably in a rolling mill, in shape preferably flat-bottomed, and with rectangular sides—all this is made plain in the statement that the sheet of Fig. 2 is bent on the dotted lines, *a-b, c-d, e-f, g-h, i-j, k-l, m-n, o-p*, to the channeled section shown in Fig. 3. The number of such channels is not essential to the invention and in each case will be determined by consideration of matters of weight, over-all dimensions, intended service, and the like. Before the sheet is so channeled (though the order of these steps is not important, except as a matter of convenience) it is slit at the part or parts where corners are to be formed; and, in case the sheet is to form the continuous side-wall of a rectangular box as shown, these places of slitting will be four, at properly spaced intervals. The metal is slit at opposite points where the margins of the channel-bottom are to extend, as indicated in the full lines *w-x, y-z*; another slit is cut across the channel-bottom, connecting at one end the slits already defined, as at *x-z*. The side-walls of the channels are then slit, and these slits in the side-walls will be arranged adjacent and preferably midway of the length of the longitudinal slits *w-x, y-z*; these slits in the side-walls are alined with one another and lie on the line of intended bending for forming the corner; they are indicated at *r-s, t-u*. After the sheet has been slit and shaped, as already described, the next step in the operation is the bending of the sheet on a transverse line to form the corner.

This bending will not, ordinarily, occur in the shop where the preceding operations have been performed; but the sheets are shipped in the form thus far described, and 5 the bending of the sheets to form the receptacle walls is done in the user's manufactory. The line of bending will be coincident with the line of the slots $r-s$, $t-u$, and the direction of bending will preferably be 10 such as to bring the protrusion of the channel inward. As the sheet is thus bent, portions of the sheet adjacent the slits will be turned out of alignment and allowed to overlap one another. The ends of the sheet are 15 secured, by overlapping and riveting as at 1—2, Fig. 1, or otherwise, to form the box-wall structure of Fig. 1.

The tongue of metal $w-x-y-z$ (Fig. 2) may be cut away (in which case, the corner when 20 bent will be that indicated in section in Fig. 7); or it may be and preferably is retained to constitute means of securing the angle more firmly. Fig. 4 shows this tongue 3 lapped around the corner on the outside and 25 riveted in the bottom of the channel on the opposite side of the corner; Fig. 6 shows it lapped in the same way but, instead of being secured by a rivet, its tip is turned through a slot formed for that purpose in 30 the bottom of the channel. Spot-welding is, of course, a known alternative to these modes of securing. It will be understood that, before the corner is bent, this tongue may be turned aside and so brought to round the 35 corner on the inside instead of on the outside of the box; and in this case it may be secured in such manner as has already been indicated or in other manner familiar to those skilled in work of this nature. Figs. 40 7 and 8 show the tongue cut away and the corner secured, in the one case (Fig. 7) by riveting through the overlapping portions of the channel-walls, as at 4, and in the other case (Fig. 8—compare Fig. 5) by the application 45 of a reinforcing and securing plate, 5. This plate, as indicated in Fig. 5, may or may not overlap the channel walls, and it may be secured by any preferred means—rivets, spot-welding, or otherwise. It will 50 be understood that the overlapping of the

channel-walls may be eliminated, if desired, by cutting away portions which otherwise would overlap; but I prefer the overlapping both of the tongue formed from the channel-bottom and the lips formed from the 55 channel-walls, as means of strengthening.

The alternative form shown in Figs. 9-11 will readily be understood by comparison with Figs. 4, 6, and 2, respectively. The longitudinal slits $w-x$, $y-z$ are formed, as 60 before; but there is a continuous transverse slit across the channel on the lines of the corner-bend, from r to u . The channel is shaped inward but the tongues 10, 11, 12, and 13 formed by the slitting are bent outward. 65 The triangular tongues 12 and 13 formed in the channel walls are bent outward and preferably held between the outwardly bent rectangular tongues 10 and 11 formed in the bottom of the channel. When the box-corner is so formed by bending, the tongues may be riveted through or otherwise secured and the tongues so arranged and extending obliquely, as indicated in Fig. 9, form a 70 brace to the structure. 75

I claim as my invention:

A wall or like structure formed of a single sheet of metal provided with a rectangular flat-bottomed channel, slit longitudinally at opposite points along the margin of the 80 bottom of said channel, and transversely across said channel bottom connecting the longitudinal slits at one end, and slit further transversely across the walls of said channel at points intermediate the length of 85 said longitudinal slits, the said sheet being further bent on a line coincident with the slits across the channel walls, and with the raised side of the sheet inward, the tongue formed by the slitting of the channel bottom as aforesaid overlapping and being secured to the adjacent portion of the channel 90 bottom.

In testimony whereof I have hereunto set my hand.

EDWARD G. CAUGHEY.
